UNITED STATES PATENT OFFICE.

BURNETT V. BUFFINGTON, OF MARYSVILLE, OHIO.

BOOK-STAND.

SPECIFICATION forming part of Letters Patent No. 240,085, dated April 12, 1881.

Application filed February 14, 1881. (No model.)

To all whom it may concern:

Be it known that I, B. V. BUFFINGTON, M. D., of Marysville, in the county of Union and State of Ohio, have invented certain new and useful 5 Improvements in Book-Stands; and I do hereby declare that the following is a full, clear, and exact description thereof, reference being had to the accompanying drawings, and to the letters of reference marked thereon, which form 10 part of this specification.

The object of this invention is to construct a device especially adapted for holding and preserving large books—such, for instance, as a dictionary—and also to adapt the said device to subserve the purpose of an ordinary stand or table when it is not desired to use 15 the said book.

To such end my invention consists in a box composed of two sections hinged together and 20 adapted, when closed and lowered between vertical standards, to serve as a stand or table by reason of the enlarged end boards of the sections constituting the table-top, and adapted, when raised and opened upon said standards, 25 to admit of the book contained therein being opened and inspected.

It also consists in the details of construction hereinafter fully described, and specified in the claims.

30 In the drawings, Figure 1 is a perspective view of the box raised and opened, and also of the supports therefor. Fig. 2 is a side elevation of the open box and portion of its supports. Fig. 3 is a vertical section with the box 35 closed and lowered; and Fig. 4 is a vertical section taken through one of the sections of the open box, a portion only of two of the standards being shown.

A A indicate four upright standards, which 40 are supported by suitable legs, C, which, if desired, can be provided with easter-wheels, to admit of the device being readily moved over the floor of a room.

D refers to the box, which is composed of 45 two equal sections, E E, hinged together by means of the hinges F, which admit of the box being opened to form a tray or holder, as shown in Fig. 1, or closed to form a box and stand or table, as shown in Fig. 3. To the 50 outer sides of the sections of this two-part box are secured the strips G G, each provided with

a longitudinal groove, H, and to the inner sides of the standards, at their upper ends, are secured the pins I, which project into the grooves of the said strips. Each section of 55 the box is composed of four sides, the sides K at the ends of the sections being considerably wider than the said sections, so that when the box is closed, as in Fig. 3, these sides K coming together will constitute a table-top or top 60 of a stand for holding various articles.

L L indicate bands or straps secured at their ends within the two sections of the box, and M indicates a book, which I have represented in several of the figures for the purpose of 65 more fully illustrating my invention.

To convert the device into a table when it is not desired to use the book, the box will be closed and let down between the standards, the pins and grooves serving to guide and steady the 70 same. In assuming the position shown in Fig. 3, the sides K of the sections will constitute the table-top, and the book, which is now inclosed by the box, will be supported by the bands or straps which are connected at their ends to the two 75 said sections, there being, as will be observed, no bottom to the box when it is thus closed, such construction being obviously necessary in order that when the box is opened to form a tray there will be no central partition therein. 80

To convert the box into a tray or book-holder, so that the book can be opened and supported, it will be necessary to raise the box until checked by the contact of the pins upon the standards with stops at the ends of the 85 grooves in the strips that are secured to the box-sections. The said sections can now be opened, the pins constituting bearings for the same to turn upon, and also supporting the same when opened, as in Fig. 2, the top ends 90 of the standards also serving as supports for the same purpose. The box being thus converted into a tray or holder, the book can be opened and inspected without raising the same from its support.

I am aware that it is not new to have a hinged box closing in between pivoted standards—as, for instance, such as are used for holding and exhibiting drawings, &c.—and hence I do not claim such, broadly, as my invention. 100

What I claim as my invention is—

1. A combined table and book-stand consisting, essentially, of the four upright standards A A, provided with pins supporting legs C C, the box D, composed of two equal sections 5 hinged together at their bottoms and provided with top boards or table-leaves, K, grooved strips G, and bands L, all constructed and adapted to form an inclosed or open book-stand or a table, substantially as herein set forth.
- 10 2. The combination, with the rigid standards provided with pins at their upper ends, of the box composed of two sections hinged together and provided with top boards, the

strips G, secured to said sections and provided with grooves receiving the pins of the 15 standards, and the bands L, secured to the interior of said sections for supporting a book when the box is closed, all constructed and arranged substantially as described.

In testimony that I claim the foregoing as 20 my own I affix my signature in presence of two witnesses.

BURNETT V. BUFFINGTON.
